UNITED STATES PATENT OFFICE.

ELMER BRADFORD PYLE, OF NEW YORK, N. Y.

LETTER-PRINTING APPARATUS.

Application filed May 19, 1923. Serial No. 640,085.

This invention relates to letter printing apparatus and particularly to apparatus of the character employed for printing letters in such manner that they shall simulate letters printed upon a typewriting machine, and the invention is directed to the provision of an improved letter printing apparatus.

It is not infrequently desired to send to a large number of different addresses, letters which are substantially identical except for the address itself. The ideal letter of this character should not be distinguishable from an individual typewritten letter and, in order to attain this result in a letter printing apparatus which is adapted to produce such letters in large quantities and at a reasonably low cost, various machines have been constructed in the past, but these only approximated the result desired and none of the machines of which I am aware actually produces a letter which is completely indistinguishable from a typewritten letter.

The means usually employed for printing addresses upon circular letters is an address plate of relatively thin metal, in the surface of which the characters constituting the address are embossed. It has heretofore been necessary, however, to place this relatively thin address plate within a protecting frame, or holder, for the purpose of preventing injury to the plate while passing through the printing apparatus, and to provide surfaces of uniform dimensions and outline to adapt the address plate to be handled by an automatic machine which, in some cases, prints the body of the letter and the address at the same operation, and, in other cases, merely adds the address to the body of the letter which has already been printed in a previous operation.

This method of producing circular or duplicate letters is unsatisfactory for one reason or another. The product is more or less easily distinguishable from an ordinary typewritten letter for the reason that it is very difficult to so adjust the apparatus that the address will be printed in proper alignment with the body of the letter, and this is true even when the address and body of the letter are printed at one operation in the machines of the prior art. Furthermore, it not infrequently happens that a portion of the address plate frame or holder will come in contact with the surface of the letter paper and cause undesirable lines or blurs to appear on the letter.

A further disadvantage of the machines of the prior art is to be found in the means now in use for adjusting the elevation of the surfaces of the type both in the body of the letter and in the address so as to secure an even impression and even printing of the letter. If the relatively short lines of type which frequently occur at the ends of paragraphs and in the address have their type surfaces at precisely the same elevation as the full length lines of type, when the impression roller is moved over the type to print the letter the short lines of type will be printed much heavier than the full length lines, with the result that these short lines stand out boldly in contrast with the remainder of the letter.

The method of correcting this difference in impression which is in use at present is to remove the type frame or "chase" from the bed of the machine, turn this type frame upside down upon a flat surface, and paste thin strips of paper along the bottoms of the full length lines so that, when the type frame is again placed in upright position in the machine, the surface of the full length lines of type will be elevated slightly above the surface of the short lines. This initial preparation of the chase, or "make-ready", as it is called, consumes a relatively large amount of time and requires the experience of an operator who is possessed of considerable skill.

For printing the address simultaneously with the body of a letter, I have discovered that an address plate of relatively thin sheet metal can be used in its original form just as it comes from the embossing machine and without the employment of any supporting frame structure or holder whatever, and, in accordance with the invention, I have provided means for utilizing such an unframed address plate for this purpose. In carrying out the invention, an address plate carriage is provided, having means for removably holding an unframed address plate, and this carriage is so arranged as to be slidable to printing position in which the address plate is brought underneath the inking ribbon in close proximity as is desired to the body of the type for printing the body of the letter. The carriage is slidable in the reverse direction to a position beyond the ribbon to permit the removal of the address plate and the insertion of a similar plate, in the same position as previously occupied by the first

plate, for the printing of the next letter.

The body of type for printing the body of the letter is, in accordance with my invention, set up in a type frame provided with means for individually and independently adjusting the elevation of the surface of the type in each line with respect to the surface of the type in the other lines and with respect to the surface of the impression element, these means being capable of actuation while the body of type remains in the printing position in the machine. The form of the adjustable support which I prefer to employ for each line of type is a wedge-shaped member which is adapted to be slid transversely of the type body, that is, longitudinally of the line of type which the member supports, and I arrange these wedge members so that they may be actuated to adjust the height of the line of type without removing the type body from the printing apparatus.

My invention further contemplates certain novel features of construction which will be understood from the following description of the invention which is illustrated, by way of example, in the accompanying drawings;

Fig. 1 is a plan view of my improved letter printing apparatus with the inking ribbon broken away to show the parts beneath it;

Fig. 2 is a vertical longitudinal section of the apparatus taken on line 2—2 of Fig. 1, and showing the address plate carriage in the printing position;

Fig. 3 is also a vertical longitudinal section taken in the same plane as Fig. 2 and showing the address plate carriage in the second or outward position;

Fig. 4 is a plan view of the address plate carriage;

Fig. 5 is a vertical longitudinal section taken on line 5—5 of Fig. 4 and also including a portion of the type frame;

Fig. 6 is a vertical cross section taken on line 6—6 of Fig. 4;

Fig. 7 is a view in perspective of an unframed address plate;

Fig. 8 is a plan view of the type frame the type therein being broken away;

Fig. 9 is a vertical cross section taken on line 9—9 of Fig. 8, showing an adjustable wedge-shaped member supporting a line of type;

Fig. 10 is an enlarged view taken on line 10—10 of Fig. 8 to illustrate one means of laterally adjusting one of the wedge-shaped members;

Fig. 11 is also an enlarged view which is taken on line 11—11 of Fig. 8 to illustrate how the lines of type are each independently supported by a separate wedge-shaped member;

Fig. 12 is a view similar to Fig. 8 showing a modification of the type frame;

Fig. 13 is a vertical cross section of the apparatus shown in Fig. 1 with the impression

roller inclined to accommodate the type frame shown in Fig. 12;

Fig. 14 is an enlarged fragmentary cross section taken on line 14—14 of Fig. 12;

Fig. 15 is a transverse section taken on line 15—15 of Fig. 12 and

Fig. 16 is a view of a modification of Fig. 9.

Referring to Figs. 1, 2 and 3 of the accompanying drawings, there is represented a supporting frame 20 for the letter printing apparatus to the upper portion of which there is secured the type bed 21. A type frame 22 in which there is placed a body of type 23 for printing the body of a letter is carried on the upper surface of the type bed 21. An extension of the type bed is provided upon the front end of the letter printing apparatus (which is to the right as viewed in the drawings) and this extension may consist of a steel plate 24 of about the same thickness as the type bed plate, this plate 24 being rigidly secured to the underside of a pair of steel bars 25 which are securely fastened, respectively, upon each side of the type bed and extend longitudinally thereof throughout substantially the entire length of the machine.

This construction of the type bed extension insures that the upper surface of the plate 24 shall be approximately level with the type bed itself and constitutes a particularly rigid supporting surface upon which the address plate carriage 26 may slide longitudinally of the machine to and from its printing position (Figs. 2 and 3). A cross bar 27 is used to tie together the outer ends of the longitudinal bars 25 and serves as a support for limiting the outward movement of carriage 26.

The address plate carriage 26 is provided with means for removably supporting an unframed address plate 28, of relatively thin metal, such as zinc, in proximity to the inner end of the carriage, so as to place this address plate in proper relation to the type 23 for the body of the letter when the carriage is slid to its inner position. An inking ribbon 29 is supported so as to be automatically fed over the surface of the type longitudinally of the type bed, the means for supporting and automatically feeding this ribbon comprising a pair of ribbon rolls 30 and 31.

An impression element consisting of a suitable roller 32, which is usually provided with a surface of rubber or similar resilient material, is mounted in an appropriate carriage 33 adapted to be moved by means of the handle 34 over the longitudinal surface of the type bed. This operation brings a sheet of letter paper 35 into printing relation with the surfaces of the type 23, the type contained on the type plate 28, and the date type 36, at one operation.

The ribbon roll 30, which is located at the back of the machine, is disposed beneath the

plane of the type surface and thus allows the impression carriage 33 to be moved over this roll and thereby reduces the space occupied by this operation of the machine. 5 The other ribbon roll 31 is supported above the plane of the type surface in order to allow the address plate carriage 26 to slide under the ribbon, and this roll is mounted in bearings 37 which may conveniently be secured to the side bars 25 at a distance in front of the type body 23 sufficient to allow the proper travel of impression carriage 33 so as to make a complete impression of the entire letter, including the date and address. 10 These bearings 37 are so constructed that ribbon roll 31 may be easily removed therefrom and the working portion of the ribbon 29 removed from the type surface for any purpose, such as for inspection, or in order 15 to change the body of the letter, or the date.

In order to accurately position the address plate carriage 26, I provide a pair of guides 38 on the type bed extension, adapted to coact with the sides of the carriage 26 as it is slid back and forth from the inner, or printing, position to the outer, or plate-removing position. These guides 38 are arranged to be laterally adjustable with respect to the 25 type bed and for this purpose a pair of steel rods 39 are provided for each of the guides 38, these rods passing through closely fitting apertures 40 in the side bars 25, their inner ends being tapped into the guides 38 30 at 41. In this manner the rods 39 are secured to the guides 38 and serve as guide members to maintain the guides 38 in parallel relation with the sides of the type bed. They may be adjusted to guide the address 35 plate carriage 26 in the proper path to carry address plate 28 in proximity to the body of the letter with one end of the address type always in accurate alignment with the ends of the lines of type in the body of the letter. 40 When the guides 38 have been adjusted to this position, they are securely clamped by means of the set screws 42, which are threaded into the side bars 25, so that their inner ends will bear against the rods 39. These 45 rods may be provided with heads at their outer ends, as shown, in order to limit the inward movement of the guides 38.

In order to hold the date type 36 in proper 50 relation with respect to the body of the letter, a small type frame 43 may conveniently be secured to one of the guides 38, as shown in Fig. 1, and the date type may be set up in this frame in the usual manner. However, if desired, frame 43 may be clamped to the type bed in the ordinary manner independently of guide 38.

The construction of the address plate carriage 26 is as follows: A metal block 44 (Fig. 4), somewhat wider than the length of the 55 address plate and long enough to clear the

ribbon roll 31 when the carriage is in the printing position, forms the body of the carriage. The inner end of this block preferably is constructed with an overhanging projection 45 which is adapted to extend over the front frame member 46 of the type frame 22 in order to bring the address plate 28 as close as possible to the type body 23. This plate 28 is held in removable position on the upper surface of the carriage 26 by means of the guides 47 and 48 and the flexible finger 49. The guides 47 and 48 consist of relatively thin strips of sheet metal secured to the inner end and left hand side, respectively, of the body 44 by any appropriate means, such as rivets or screws, and the upper edges of these relatively thin plates project above the surface of the body 44 a distance which is approximately equal to the thickness of the address plate 28, as may be seen in Fig. 5, and these projecting portions of the guides 47 and 48 are preferably bent slightly toward the address plate so as to more effectively grasp the edges of the plate 60 to hold it in position.

A flexible finger 49 is fixed at one end in any suitable manner, as by means of a pair of screws, to a longitudinal bar 50 which extends from the front end of the body 44 toward the inner end thereof to a point near address plate 28. Bar 50 is preferably rectangular in cross section and moves in a closely fitting slot or groove 51 provided in the surface of the carriage body 44. Flexible finger 49 projects inwardly from the end of the bar 50 and preferably widens out, as shown in Fig. 4, to provide a relatively long line of contact with the address plate 28, the inner end of this widened portion having a surface 52 adapted to make frictional engagement with the upper surface of the relatively thin sheet metal plate 28, and also having a surface 53 adapted to coact with the edge of plate 28 opposite the guide 47, for the purpose of holding the plate against this 70 guide.

Near the front end of the carriage 26, a handle 54 is attached to the bar 50 by which flexible finger 49 may be withdrawn from the position shown in Fig. 4 so as to release it 75 from engagement with plate 28, for the purpose of removing this address plate and inserting a different one in place of it. A pin or screw 55 is so placed in the upper surface of bar 50 that it comes in contact with the stationary stop 56 secured to the carriage body 44 soon after the plate 28 is released by finger 49, and the co-action of pin 55 with stop 56 results in the sliding of the address plate carriage 26 when a continued pull on the handle 54 is exerted.

For the purpose of accurately adjusting the elevation of the surface of the type in address plate 28, the carriage 26 is provided with the three adjusting screws 57, which are threaded 80

into the carriage body 44 is such manner as to have their ends brought into contact with the type bed upon the surface of which the carriage 26 slides. Two of these screws 57 are located near the inner end of the carriage and the third near its outer, or front, end, thus providing a three-point support for the carriage upon the surface of the type bed.

The construction of carriage body 44 may be varied to a considerable extent. For example; instead of constructing the carriage body 44 of a solid block of metal, a steel or iron casting, such as illustrated in Fig. 6, may be used; or by elevating somewhat the supporting plate 24 the thickness and weight of the carriage may be materially reduced.

Returning now to the description of the type frame 22, this element of the letter printing machine is made with three of its sides 20 58 (Figs. 1 and 8) of usual thickness and strength, but, the front end 59 of this frame may, if desired, be reduced to approximately the thickness of a line of type.

By causing the address plate carriage to extend over the end frame, the position of the address plate with respect to the type body is made extremely flexible, and it is possible to print the address relatively close to the body of the letter even when the lowest line of 30 the address type is impressed at some distance from the edge of the plate.

Referring now to Figs. 8 to 11 of the accompanying drawings, details of the construction of the type frame 22 are here illustrated. A bottom member 60 is securely fastened to the side members 58 of the type frame, the upper surface 61 thereof being inclined (see Figs. 9 and 10). A plurality of wedge-shaped members 62 rest upon the bottom member 60, these 35 wedge-shaped members having their lower surfaces inclined by an amount corresponding to the inclination of surface 61, so that the upper surfaces 63 of the wedge-shaped members are horizontal. The number of 40 these wedge-shaped members 62 corresponds with the number of lines of type which the frame 22 is adapted to carry, so that each line of type is individually supported by one of 45 these wedge-shaped members in co-operation with the bottom 60. The outer ends of members 62 extend into recesses beneath the side members 58 and are held in transversely 50 slideable relation with the bottom member 60.

In order to impart a transverse movement to these members 62, a plurality of adjusting pins 64 are tapped into one of the side members 58, the number of these pins corresponding to the number of the wedge-shaped members 62, and each of these screws 64 being arranged to engage its corresponding wedge member, as will be seen in Fig. 10 where a cross section through a single one of these adjusting pins 64 is illustrated. By referring to this figure, an eccentric projection 65 will be seen on the lower end of pin 64, and this projection fits

closely into a drilled hole in the head 66 of its corresponding wedge member 62. Thus, by inserting a screw driver in the exposed slot 67 in the upper end of the adjusting pin, it may be rotated and the eccentric motion of 70 the projection 65 will cause the wedge 62 to slide laterally of the type frame.

The maximum lateral movement of the wedge member is obtained by rotating screw 75 64 through an angle of 180° and the dimensions of the screw and the inclination of the coacting inclined surfaces are so proportioned that a sufficient vertical movement will thereby be imparted to the type 23 to effect any vertical adjustment of any of the lines 80 of type which are found to print more heavily than desired. As shown in Fig. 11, the upper edges of the wedge-shaped members 62 are preferably beveled slightly, as shown at 68, in order to allow for a slight longitudinal displacement of the lines of type without interfering with the adjustability of the individual lines.

In operating the improved letter printing apparatus of my invention, the address plates 28 are first made on an embossing machine, the address characters being embossed on the surface of plates of relatively thin metal, such as zinc, or the like. These address plates are ready to be used in my improved letter printing apparatus as soon as they come from the embossing machine, and without further operation of any kind, such as framing them in a plate holder.

The type 23 for the body of the letter is 100 set up in frame 22, and, at the commencement of this operation, all the wedge-shaped members 62 are slid over against the right hand frame member 58 (Fig. 9), in which position the upper surfaces 63 of all of these type 105 supporting members lie in the same plane. The type 23 is then set up in the usual manner and any short lines of type, such, for example, as those which may occur at the ends 110 of paragraphs, are lowered slightly by turning the adjusting screws 64 corresponding to these short lines. The type frame is then inserted in the letter printing apparatus in the position shown in Figs. 1, 2 and 3, and the date type 36 is set up in the frame 43, 115 which is preferably constructed like frame 22 to allow of the adjustment of the individual lines.

An address plate 28 is then placed against the guides 47 and 48 and the flexible finger 120 49 moved into place by means of handle 54, whereby the address plate is firmly held in position upon the carriage 26. Carriage 26 is now moved to its inward position, bringing the address plate into close proximity 125 to the type 23 of the body of the letter. The left hand edge 69 of the address type is aligned by the eye, or by means of a straight edge, with the left hand edge 70 of the type 23 by sliding the guides 38 laterally of the 130

type bed, and when this alignment has been accomplished the set screws 42 are set up to hold the guides 38 firmly in place, care being taken that there is a close sliding fit 5 between the carriage 26 and the guides, so that the carriage will slide freely but not admit of any side play.

Then the inking ribbon 29 is placed in position over the type surfaces by placing the 10 ribbon roller 31 in its removable bearings 37. A protecting outline stencil or guard of thin cardboard may now be placed over the ribbon to prevent the letter paper from coming into contact with the ribbon except within 15 the type areas.

A sample impression is next taken by laying a sheet of letter paper over the type surface and moving the impression roller 32 throughout a full stroke by means of the 20 handle 34. If, after examination of the sample impression, it is found that further adjustment is necessary, either in the elevation in the surface of the type or in the alignment of the address plate, such adjustments 25 may easily be made by simply lifting the stencil and the inking ribbon 29 so as to expose the adjusting screws 64 for the individual lines of type. The adjustment of the alignment of the address plate may be made 30 without even removing the ribbon 29, inasmuch as the adjustments of the carriage 26 are always accessible.

After the machine is in complete adjustment, the requisite number of copies of the 35 letter to the various addresses may be made, a new address plate 28 being inserted for each impression. In order to remove the old address plate and insert a new one, the operator pulls upon the handle 54 which first releases flexible finger 49 from the address plate 40 which has just been printed and then, by continued pressure upon the handle 54, the pin 55 engages stop 56 and causes the carriage 26 to be moved to the outer position, as shown in 45 Fig. 3, where the address plate is exposed beyond the ribbon roller 31 and may be removed by the fingers, and another one placed against the stops 47 and 48. Then, by pressing upon the handle 54 in the opposite direction, flexible finger 49 is caused to engage 50 the new address plate 28 and hold it firmly in the proper position against the guides. Further pressure upon handle 54 moves the carriage 26 to its inner position, where the 55 address plate 28 is brought again into printing position ready to print the new letter.

Referring now to the modifications of the type frame which are illustrated in Figs. 12 to 16, the inclination of the bottom of the 60 type frame referred to previously is essentially an inclination of this surface with respect to the surface of the impression roller, and this may be accomplished in several different ways. The essential requirement is 65 that the wedge-shaped members supporting

the individual lines of type be so proportioned with respect to the angle which the bottom of the type bed makes with the impression roller, that the surface of each line of type is supported in parallel relation to 70 the surface of the impression roller.

In the apparatus previously described, the impression element is horizontal or, in other words, parallel with the bed of the letter printing apparatus, the upper surface of the 75 bottom of the type frame is inclined with respect to the horizontal, and the wedge members which rest upon the bottom have the same angle of inclination, hence they support the lines of type in horizontal position 80 parallel with the horizontal impression roller.

In the modification of the construction of the type frame shown in Figs. 12 to 15, the impression roller is inclined with respect to the horizontal type bed so that it is unnecessary to incline the surface of the bottom of the type-frame, and, inasmuch as the angle between the upper and lower surfaces of the wedge members is the same as the angle of 85 inclination of the impression roller, the surfaces of the lines of type are supported in parallel relation to the surface of the inclined impression roller. 90

Thus, in Fig. 13 the impression roller 32 is mounted with its axis inclined with respect to the horizontal surface of the type bed 21 by a relatively small angle. This may be readily done by raising the guide ways 71 on one side of the machine along which the impression carriage 33 travels; also at the same time raising the resilient track 72, on which the driving wheel 73 rolls. The bottom 74 of the type frame 75 consists of a flat metal plate of uniform thickness and the wedge members 76 are metal bars having the same angle between their upper and lower surfaces as the angle of inclination of the axis of impression roller 32 with respect to the horizontal surface of type bed 21. In this way, the upper surface of the type 23 is supported in parallel relation with respect to the surface of the impression roller. The operation of this apparatus is equally as good as the operation of the apparatus having a 100 horizontally mounted impression roller. 110

The construction of the type frame and of the individual wedges may also be modified in other respects. Instead of utilizing the adjusting pins 64, shown in Figs. 8 to 11, for the purpose of sliding the wedge members horizontally, the construction illustrated in Figs. 12 to 15 may be employed. As here shown, the bottom plate 74 of the type frame is secured to the side and end members of the type frame, this frame being made of appropriate size and shape for the letter printing apparatus with which it is to be used. An intermediate bar 77 is rigidly secured between the end frame members, as by the means of the screws 78, this bar being spaced from 115 120 125 130

the bottom 74 so as to allow the wedge members 76 to slide thereunder.

The parallel ends 79 of the wedge-shaped members 76 project outwardly to the right 5 of bar 77 into a space 80 between this bar and the right-hand side frame, and these ends are not provided with heads 66 as previously described in connection with Fig. 10, but they are provided with recesses 81 in which a 10 pronged adjusting tool may be inserted. By means of this instrument, the wedge members may be slid transversely of the type frame to effect the relative adjustment of the elevation of the surfaces of the individual lines of type 15 with respect to the surface of the impression roller.

In Fig. 12, the majority of wedge members 76 are in their normal position, in which they are shoved over to the left as far as possible 20 and in which the lines of type supported thereby are at the same, and maximum, elevation. A few of these wedge members such as those indicated by reference numeral 82, however, have been slid to the right in order 25 to drop the surfaces of the lines of type supported by these members by varying distances with respect to the remaining lines of type and also with respect to the surface of the impression roller. The lines supported by 30 wedge members 82 being short lines of varying length would, if they were held at the same elevation as the long lines of type, be printed in relatively heavy type and impair the appearance of the finished letter.

The type 23 is set up in the type frame 75 in the ordinary manner, the usual "furniture" 35 83 and 84 being used to fill up the spaces between the margins of the type and the sides of the type frame. Adjusting screws 85 are 40 threaded through bar 77 in position to bear upon the surface of the furniture strip 84 so as to clamp the type firmly in place after the proper adjustment of the short lines has been made. Clamping screws 86 are also provided 45 in one end of the type frame which are positioned so as to coact with the wedge members and clamp the entire body of wedges longitudinally of the type frame against the 50 end opposite these screws. These clamping screws are also tightened up after the adjustment of the short lines has been made so as to retain all of the wedge members in the positions to which they have been adjusted.

In Fig. 16 there is illustrated a modified 55 form of type frame having an inclined bottom for use on a letter printing machine in which the axis of the impression roller is horizontal. In the form of construction shown in Fig. 9, the bottom plate 60 is thinner at the left-hand edge than at the right or, in other words, the bottom itself is wedge-shaped in cross section. The upper surface 60 of the bottom of the type frame shown in Fig. 16 is inclined, although it consists of a 65 flat metal plate 87 of uniform thickness.

The upper surface of this plate is inclined by elevating one side of the type frame, for example, the left hand side. A convenient way of supporting the elevated side is by means of two or more screws 88 threaded vertically 70 through the side frame and cooperating with the surface of the type bed 21. Thus, by turning these adjusting screws the surface of plate 87 may be inclined by an amount which will compensate for the angle of the wedge 75 member 76 resting thereon and bring the upper surface 90 of the type into parallel relation with the type bed 21 and with the surface of the impression roller (not shown).

The use of these various modifications 80 either in place of or in conjunction with the letter printing apparatus described in connection with Figs. 1 to 11 effects the mode of operation of the letter printing apparatus only in such manner as may be well understood from the description of the construction of the modifications. Hence, it is not necessary to add to the description of the operation already given in detail.

By the use of this improved letter printing 85 apparatus I am able to produce circular letters in quantity, the quality of printing of which is such that it is very difficult to distinguish them from individual typewritten letters inasmuch as the impression is uniform 90 throughout the body of the letter, the address, and the date; and the address is in perfect alignment with the body of the letter. Moreover there are no impressions caused by 95 the holder of the address plate, as in machines of the prior art. In addition to securing a better quality of product than by any other apparatus of which I am aware, the invention produces this result at a considerable saving in cost, because of the simplicity 100 of the improved apparatus which makes it relatively inexpensive to manufacture, and because no frames or plate holders are required for the address plates. This latter item in itself is a very considerable one, especially where it is desirable to circularize an 105 address list of several thousand names.

I claim:

1. An apparatus of the character described comprising, a type bed, a body of 115 type carried thereby for printing the body of a letter, an impression element movable over said type, an inking ribbon between the type and the impression element, and an address plate carriage provided with means 120 for removably holding an address plate, said carriage being slidable in the plane of the type body to printing position beneath said ribbon to bring the address plate into proximity to said body of type and to a position 125 beyond the ribbon to permit the removal of the address plate.

2. An apparatus of the character described comprising, a type bed, a body of 130 type carried thereby for printing the body of

- a letter, an impression element movable over said type, an inking ribbon between the type and the impression element having a fixed supporting roll disposed above the type surface and beyond the limit of movement of said impression element, an address plate carriage provided with means for removably holding an address plate, said carriage being slidable to a position inside of said supporting roll to bring the address plate into proximity to said body of type beneath the inking ribbon and also being slidable to a position outside of said supporting roll to permit the removal of the address plate.
5. An apparatus of the character described comprising, a type bed, a body of type carried thereby for printing the body of a letter, an impression element movable over said type, an inking ribbon between the type and the impression element, and an address plate carriage slidable to printing position beneath said ribbon and to a position beyond the ribbon to permit the removal of the address plate, and means on said carriage for removably holding an unframed address plate of relatively thin metal.
4. An apparatus of the character described comprising, a type bed, a body of type carried thereby for printing the body of a letter, an impression element movable over said type, an inking ribbon between the type and the impression element, an address plate carriage slidable to printing position beneath said ribbon and to a second position beyond the ribbon to permit the removal of the address plate, and means on said carriage for removably holding an unframed address plate of relatively thin sheet metal, said means comprising guides for two edges of said plate, and a flexible finger movable into a position in contact with the upper surface of the plate.
5. An apparatus of the character described comprising, a type bed, a body of type carried thereby for printing the body of a letter, an impression element movable over said type, an inking ribbon between the type and the impression element, an address plate carriage slidable to printing position beneath the said ribbon and to a second position beyond the ribbon to permit the removal of the address plate, and means on said carriage for removably holding an unframed address plate of relatively thin sheet metal, said means including a flexible finger movable into position in contact with the upper surface of the plate.
6. An apparatus of the character described comprising, a type bed, a body of type carried thereby for printing the body of a letter, an impression element movable over said type, an inking ribbon between the type and the impression element, an address plate carriage slidable to printing position beneath said ribbon and to a second position beyond the ribbon to permit the removal of the ad-
- dress plate, and means on said carriage for removably holding an unframed address plate of relatively thin sheet metal, said means comprising guides for two edges of said plate, and a flexible finger slidable into frictional engagement with the upper surface of the plate and having a portion adapted to co-act with an edge of the plate to hold it against one of said guides.
7. An apparatus of the character described comprising, a type bed, a body of type carried thereby for printing the body of a letter, an impression element movable over said type, an inking ribbon between the type and the impression element, an address plate carriage slidable to printing position beneath said ribbon and to a second position beyond the ribbon to permit the removal of the address plate, and means on said carriage for removably holding an unframed address plate of relatively thin sheet metal, said means comprising a guide for the inner edge of the address plate secured to the inner end of said carriage, a second guide for one end of the address plate disposed near the side of said carriage, and a flexible finger slidable longitudinally of said carriage for engaging the upper surface and the edge of the address plate opposite to said first mentioned guide.
8. An apparatus of the character described comprising, a type bed, a type surface carried thereby for printing the body of a letter, an impression element movable over said type surface, an inking ribbon between the type surface and the impression element, an address plate carriage mounted to slide longitudinally of the type bed to carry an address plate into and out of printing position adjacent the front end of said body of type, means on said carriage for removably holding an unframed address plate, guides operatively positioned to coact with the address plate carriage, and means for laterally adjusting said guides in order to align the address with the body of the letter.
9. An apparatus of the character described comprising, a type bed, a type surface carried thereby for printing the body of a letter, an impression element movable over said type surface, an inking ribbon between the type surface and the impression element having a supporting roll disposed above the type surface and beyond the limit of movement of the said impression element, an address plate carriage provided with means for removably holding an unframed address plate of relatively thin sheet metal, means for vertically adjusting said carriage to level the address type with the type for the body of the letter, guides cooperating with said carriage, means for adjusting said guides to bring one edge of the address type into alignment with one edge of the type for the body of the letter, said carriage being slidable longitudinally of the type bed to bring the address plate into

printing position beneath the inking ribbon and adjacent the body of type, and to a second position to move the address plate beyond the supporting roll for the inking ribbon for the purpose of replacing said address plate with another of the same character.

10. An apparatus of the character described comprising, a type bed, a body of type carried thereby for printing the body of a letter, an impression element movable over said type, an inking ribbon between the type and the impression element, an address plate carriage slidable to printing position beneath the ribbon and to a position beyond the ribbon to permit the removal of the address plate therefrom, means on said carriage for removably holding an address plate, said means including a flexible finger cooperating with the upper surface and one edge of the address plate, and a handle for said carriage for sliding it to and from the printing position, said handle being operatively associated with said flexible finger to automatically release the address plate as the carriage is withdrawn from the printing position.

11. In an apparatus of the character described, the combination of a type bed, a body of type thereon, an impression element, and means for adjusting the elevation of individual lines of type with respect to the type bed, said means being operable while the body of type is in printing position upon the type bed.

12. The combination with an apparatus of the character described, of a type frame provided with wedging means slidable with respect thereto for independently adjusting the elevation of the surface of individual lines of type.

13. An apparatus of the character described comprising, a type bed, a type frame carried thereby and holding a body of type for printing the body of a letter, an inking ribbon supported in operative position above the surface of said type, and an impression element movable thereover, said type frame being provided with means for vertically adjusting individual lines of type while the body of type is in printing position upon the type bed.

14. In an apparatus of the character de-

scribed, the combination of an impression element having a resilient surface, and means for adjusting the elevation of the surface of individual lines of type with respect thereto, said means being capable of actuation while the type remains in printing position.

15. The combination with an apparatus of the character described, of a type frame having cooperating wedging members, one for each line of type, and means for sliding one of these members horizontally relative to the other to cause a vertical adjustment of the line of type supported thereby with respect to the remainder of the type body.

16. The combination with an apparatus of the character described, of a type frame having a bottom member the upper surface of which is inclined transversely of said frame, each line of type being supported by a wedge-shaped transversely slidable member resting upon said inclined bottom surface, and means for sliding each wedge-shaped member transversely of the bottom surface of the frame to effect a vertical adjustment of the individual lines of type.

17. An apparatus of the character described comprising, a type frame, an impression roller supported at an angle to the bottom of said frame, a plurality of wedge members resting upon said bottom and each supporting a line of type with its surface parallel to said roller, said members being slideable upon said bottom to provide for adjusting the elevation of the surface of individual lines of type with respect to the surface of the impression roller.

18. The combination, with an apparatus of the character described, of a type frame having a side member, a bottom member, a plurality of wedge-shaped members resting on said bottom and each supporting an individual line of type, and a corresponding number of adjusting pins rotatably mounted in the type frame, each having an eccentric projection on its bottom end cooperating with an aperture in its corresponding wedge-shaped member to impart a transverse movement to the wedge-shaped member when said screw is rotated.

In testimony whereof I affix my signature.
ELMER BRADFORD PYLE.
